Primary Examiner—Raphael Barkai*Assistant Examiner*—Mitchell I. Siegel*Attorney, Agent, or Firm*—A. Burgess Lowe; Richardson B. Farley**[57] CLAIM**

The ornamental design of a vacuum cleaner conversion arrangement, as shown and described.

DESCRIPTION

FIG. 1 is a left side elevational view of our new inventive design for a vacuum cleaner conversion arrangement;

FIG. 2 is a front elevational view thereof;

FIG. 3 is a right side elevational view thereof;

FIG. 4 is a rear view thereof;

FIG. 5 is a top plan view thereof; and,

FIG. 6 is a bottom plan view thereof.

That portion of the illustration shown in chain dotted lines represents only environment and forms no part of the invention.
